CONTROL SYSTEM

Glenn A. Caldwell, Swissvale, and George R. Shaw, Wilkinsburg, Pa., assignors to Westinghouse Electric & Manufacturing Company, East Pittsburgh, Pa., a corporation of Pennsylvania

Application May 11, 1932, Serial No. 610,530

12 Claims. (Cl. 80—47)

Our invention relates, generally, to control systems and apparatus and it has particular relation to electrical systems for controlling the operation of mills for the rolling of sheet material.

5 The object of our invention, generally stated, is to provide control apparatus for rolling mills which shall be simple, reliable and efficient in operation and readily and economically manufactured and installed.

10 The principal object of our invention is to provide for automatically controlling the operation of sheet rolling mills.

Another object of our invention is to provide for reducing to a minimum the time required to 15 traverse a complete cycle of operation in a sheet rolling mill.

20 A further object of our invention is to provide for insuring a complete automatic cycle of operation of the mill after a cycle of operation has been initiated.

25 A still further object of our invention is to provide for automatically reversing the feeding means in a sheet rolling mill to a forward direction prior to the completion of a cycle of operation and after the manual control means is moved to the "off" position.

Other objects of our invention will, in part, be obvious and, in part appear hereinafter.

30 Our invention, accordingly, is disclosed in the embodiment hereof shown in the accompanying drawings, and comprises the features of construction, combination of elements and arrangement of parts which will be exemplified in the construction hereinafter set forth, and the scope of the 35 application of which will be indicated in the appended claims.

For a more complete understanding of the nature and scope of our invention, reference may be had to the following detailed description taken 40 in connection with the accompanying drawings, in which:

Figure 1 is a view, in side elevation, of a sheet rolling mill of the type for which the control system of our invention is suitable.

45 Fig. 2 is a view, in top elevation, of the mill shown in Fig. 1, and showing in addition, the control cabinet; and,

Fig. 3 is a diagrammatic view of the electrical 50 circuits which may be used in practicing the invention.

In general, the invention comprises a two-high rolling mill provided with rolls continuously rotatable in one direction only and having on opposite sides thereof passer and catcher tables.

55 The tables are each provided with endless con-

veyors which are driven by reversible electric motors.

The sheet on which a rolling operation is to be performed is positioned on the passer table and is fed by the conveyor thereon through the rolls and to the conveyor on the catcher table. As soon as the trailing end of the sheet leaves the passer table and the leading end arrives at the catcher table, circuits are set up which cause the conveyors on both tables to reverse after a predetermined time to move the sheet back toward the passer table.

In order to position the tables so that the sheet may be returned without passing it between the rolls and thereby necessitating their reversal, the 15 tables are hinged and are provided with motors which serve to elevate the ends of the tables adjacent the rolls to a position where the rolls are cleared and the sheet may be returned to the passer table. The operation of the elevator 20 motor individual to the catcher table, is initiated a predetermined time after the sheet leaves the passer table and after it has arrived on the catcher table. When the catcher table has been moved to a predetermined position, the elevator 25 motor individual to the passer table is energized and the passer table is elevated to receive the sheet as it is returned from the catcher table.

As soon as the trailing end of the sheet leaves the catcher table and the leading end arrives back 30 on the passer table, circuits are completed which, after a predetermined time, cause the conveyors on both tables to reverse to the forward feeding direction.

The elevator motor individual to the catcher 35 table is energized a predetermined time after the sheet leaves the catcher table and arrives on the passer table and it is thereby lowered to the initial position. After the catcher table has been moved downwardly to a predetermined position, 40 the elevator motor individual to the passer table is energized and the passer table is thereby returned to the initial position and the cycle of operation is repeated.

Suitable limit switches and brakes are provided 45 in conjunction with the elevator mechanisms for stopping the movement of the tables at the upper and lower limits of travel.

In order to provide for initiating the functioning of the apparatus in accordance with the movement of the sheet from and to the tables, trigger switches are located at the ends of the tables adjacent the rolls. These switches are positioned in the path of the sheet and serve to com- 50

plete control circuits as long as the sheet is in engagement therewith.

The functioning of the entire control equipment is initiated by manual control means after 5 the sheet is moved on the passer table to the position where the trigger switch individual to that table is operated to the closed position. In order to insure that a complete cycle of operation will be performed, even if the manual control means is released, contact segments are provided on the limit switch individual to the passer table whereby the manual control means is rendered ineffective to arrest the automatic functioning of the apparatus after the passer table 10 has started up and until it is returned to the initial position.

In the event that it is desirable to stop the automatic functioning of the apparatus at the end of a complete cycle of operation, it is also 20 desirable to stop the conveyor on the passer table and actually reverse it to prevent coasting and to bring the sheet to a position where it may be inspected by the operator. This function is accomplished by the use of a plugging relay which 25 completes circuits for plugging the conveyor motors for a predetermined length of time after the control system has been de-energized.

Referring now to Figs. 1 and 2 of the drawings, the apparatus there shown comprises a two-high 30 rolling mill shown generally at 10, which is provided with rolls 11 and 12. The rolls 11 and 12 may be rotated constantly in one direction through shaft 13 by means of a suitable source of power, not shown. The mill 10 is provided 35 with uprights 14 and 15 for mounting the rolls 11 and 12 and a bed-plate 16, upon which the apparatus to be hereinafter described is located.

In order to feed a sheet on which a rolling operation is to be performed to the rolls 11 40 and 12, a passer table, shown generally at 17, is provided on the left-hand side of the mill, while a catcher table, shown generally at 18, is provided on the right-hand side, as illustrated. The passer and catcher tables 17 and 18 comprise 45 side-members 19, 20, 21, and 22, which are pivoted on shafts 25 and 26 that are journaled in pedestal bearings 27 and 28. The ends of the side-members adjacent the rolls 11 and 12 are secured together by means of cross-members 29 50 and 30, as shown.

In order to convey the sheet to the rolls 11 and 12, and to carry it away from them, the passer table 17 is provided with chains 33 and the catcher table 18 is provided with chains 34, 55 which are driven by sprocket wheels 35 and 36, which are secured to shafts 25 and 26, respectively, as by means of set screws 37 and 38. The chains 33 and 34 are positioned near the rolls 11 and 12 by means of additional sprocket wheels 59 and 60 which are secured to shafts 41 and 42, respectively, by means of set screws 43 and 44. It will be observed that the shafts 41 and 42 are journaled in the side-members 19, 20 and 21, 60 22 at the ends adjacent the rolls 11 and 12.

The chains 33 and 34 are driven respectively, 65 in this instance, by means of a polyphase squirrel-cage passer chain motor 45 and a polyphase squirrel-cage catcher chain motor 46. The motors 45 and 46 are mounted on the bed-plate 16 and serve to drive the shafts 25 and 26 through the agency of pinions 47 and 48 which mesh respectively with gear-wheels 49 and 50 that are keyed by suitable means to the shafts 25 and 26.

As shown diagrammatically in Fig. 3 of the 70 drawings, the motors 45 and 46 comprise squirrel-

rel-cage rotors 53 and 54 and field windings 55 and 56.

In order to control the operation of the mill in accordance with the movement of the sheet on the tables 17 and 18, trigger switches 57 and 58 are mounted respectively on the cross-members 29 and 30, as illustrated. The trigger switches 57 and 58 may be of any suitable type which serve to complete an electrical circuit when the sheet, on which the rolling operation is 10 being performed, engages therewith. These switches are also of a type which complete the electrical circuit when engaged from either direction by means of the sheet.

After the sheet has once passed between the 15 rolls 11 and 12 and is received on the catcher table 18, it is desirable to so position the tables 17 and 18 that the rolls 11 and 12 are cleared, thereby permitting the return of the sheet to the passer table 17 on reversal of the chains 33 20 and 34. In order to elevate the tables 17 and 18 to the dotted positions shown in Fig. 1, elevator mechanisms, shown generally at 59 and 60, are provided.

The elevator mechanisms 59 and 60 comprise 25 a polyphase squirrel-cage passer elevator motor 63 and a similar catcher elevator motor 64 which serve to rotate gear-wheels 65 and 66 through the agency of pinions 67 and 68, which mesh therewith, as shown. The gear-wheels 65 and 66 are 30 provided with pins 69 and 70 which are eccentrically located relative to the axis of rotation of the gear-wheels 65 and 66. Connecting rods 71 and 72 serve to transmit the motion of the pins 69 and 70 to the tables 17 and 18. The 35 connecting rods 71 and 72 are pivotally connected to the side-members 19 and 21 by means of suitable bolts 73 and 74, as illustrated.

It will be observed that a complete revolution 40 of the gear-wheels 65 and 66 causes the tables 17 and 18 to be raised from the position shown to dotted position and back again to the position shown.

As shown more clearly in Fig. 3 of the drawings, the motors 63 and 64 comprise squirrel-cage 45 rotors 75 and 76 and field windings 77 and 78.

In order to arrest further operation of the passer and catcher elevator motors 63 and 64 at the upper and lower limits of travel, limit 50 switches 81 and 82 are provided. In addition, brakes, shown generally at 83 and 84, are provided for insuring the stopping of the elevator mechanisms when the electrical controls are de-energized. The brakes 83 and 84 are provided 55 with compression springs 85 and 86 for applying the brakes and with solenoids 87 and 88 for releasing them.

The electrical control equipment for the mill may be housed in the controller, shown generally 60 at 89, which is a convenient location from which the operator may observe the functioning of the mill, and at the same time, be in a position to gauge the thickness of the plate after a complete 65 cycle of automatic operation has been performed.

Referring now particularly to Fig. 3 of the drawings, the functioning of the apparatus is initiated 70 by means of a master control switch 91 which serves to apply control energy from the conductors 92 and 93 which are connected to a suitable source of direct current through switches 94 and 95 and emergency stop switch 96.

The master switch 91, in conjunction with the trigger switches 57 and 58, serves to energize a 75 passer trigger relay 97 and a catcher trigger relay

98, depending upon the position of the sheet in the mill.

The trigger relays 97 and 98 serve to energize respectively a chain-forward time-limit relay 99 and a chain-reverse time-limit relay 100, which in turn serve to energize respectively a chain-forward motor relay 101 and a chain-reverse motor relay 102.

It will be observed that the motor relays 101 and 102 are arranged to connect the motors 45 and 46 to conductors 103, 104, and 105 in such manner that the energization of the motor relay 101 causes the motors 45 and 46 to rotate in one direction while the energization of the motor relay 102 energizes the motors to rotate in a reverse direction. The conductors 103, 104, and 105 may be connected by means of a switch 106 to a suitable source of three-phase alternating current.

The trigger relays 97 and 98 also serve to energize respectively a time-limit catcher elevator-up relay 107, and a time-limit catcher elevator-down relay 108 which in turn serve to energize respectively a catcher elevator brake relay 109 and a passer elevator brake relay 110.

The brake relays 109 and 110 serve to energize the solenoids 87 and 88 respectively of the brakes 83 and 84, and at the same time, to energize respectively the passer elevator motor relay 111 and the catcher elevator motor relay 112, which serve to connect their respective motors 63 and 64 to the conductors 103, 104, and 105.

As set forth hereinbefore, the upper and lower limits of travel of the tables 17 and 18 are controlled by means of the limit switches 81 and 82. The limit switch 81 is provided with contact fingers 113 through 118 and contact segments 119, 120 and 121. The limit switch 82 is provided with contact fingers 122 through 129 and contact segments 130, 131, 132, and 133. The functioning of the contact fingers and segments of the limit switches 81 and 82 will be described in detail hereinafter.

In order to permit the plugging of the chain motors 45 and 46 to prevent coasting and to return the sheet to a position where it may be inspected after the master control switch 91 has been moved to the "off" position, a plugging time-limit relay 136 is provided, which serves to energize the motor relay 101 for a predetermined length of time after the switch 91 has been operated to the "off" position.

The time-limit relays 99, 100, 107, 108, and 136 are of the type shown in Patent No. 1,753,983, issued to W. G. Cook, and assigned to the Westinghouse Electric and Manufacturing Company. These relays are each provided with a neutralizing coil 137 which may be connected in series-circuit-relation and through a resistor 138 to the energized control conductors 92 and 93. The timing of each of the relays may be adjusted by means of rheostats 139, each of which serves to shunt the main winding 140 of the time-limit relays. Additional time-adjustment may also be secured by varying the tension of the springs 141 by means of the nuts 142.

In order to illustrate the functioning of the apparatus described hereinbefore, a complete cycle of operation will be carried through in detail. It is assumed that a sheet is positioned on the passer table 17 and is in engagement with the trigger switch 57 and that the master control switch 91 has been depressed to the "on" position. The passer trigger relay 97 will then be energized.

The circuit for energizing the passer trigger relay 97 may be traced from the energized con-

ductor 93 through conductor 143, contact members 144 of the master control switch 91, conductors 145 and 146, energizing winding 147 of passer trigger relay 97, conductor 148, contact members 149 of the trigger switch 57 and conductors 150 and 151 to the energized conductor 92.

The energization of the passer trigger relay 97 causes the energization of chain forward time-limit relay 99 and time-limit catcher elevator-up relay 107, as set forth hereinbefore.

The circuit for energizing relay 99 may be traced from the energized conductor 93 through conductor 153, winding 140 of relay 99, conductor 154, contact members 155 of relay 97 and conductors 156 and 157 to the energized conductor 92.

The circuit for energizing relay 107 may be traced from the energized conductor 93 through conductor 153, winding 140 of relay 107, conductor 158, contact members 159 of relay 97 and conductors 156 and 157 to energized conductor 92.

The energization of the chain-forward time-limit relay 99 causes the energization of chain-forward motor relay 101, which serves to connect the motors 45 and 46 to the conductors 103, 104 and 105 over obvious circuits, thereby causing the chains 33 and 34 to move in a forward direction.

The circuit for energizing motor relay 101 may be traced from the energized conductor 93 through conductors 153 and 160, contact members 161 of relay 99 which are now closed, conductors 162 and 163, winding 164 of relay 101, conductor 165, closed contact members 166 of relay 100 and conductor 157 to energized conductor 92.

The energization of relay 101 serves to complete a holding circuit for itself which may be traced from the energized conductor 92, through conductor 167 and contact members 168 to conductor 163 and the circuit associated therewith, which has been previously traced.

The sheet is then passed between the rolls 11 and 12 and arrives on the catcher table 18, the leading end engaging the trigger switch 58 and the trailing end disengaging the trigger switch 57. The release of the trigger switch 57 de-energizes the passer trigger relay 97, which in turn causes the de-energization of the windings 140 of relays 99 and 107. However, the relays 99 and 107 do not permit their armatures to move to the de-energized position until the time has elapsed for which these relays are set.

The engagement of the sheet with the trigger switch 58 causes the energization of catcher trigger relay 98, which in turn causes the energization of the time-limit catcher elevator-down relay 108 and the chain reverse time-limit relay 100, as set forth hereinbefore.

The circuit for energizing trigger relay 98 may be traced from the energized conductor 93 through conductor 143, contact members 144 of the master control switch 91, conductors 145 and 146, winding 169 of trigger relay 98, conductor 170, contact members 171 of trigger switch 58 and conductors 172, 150 and 151 to the energized conductor 92.

The circuit for energizing relay 100 may be traced from the energized conductor 93 through conductor 153, winding 140 of relay 108, conductor 173, contact members 174 of trigger relay 98 and conductors 175 and 157 to energized conductor 92.

The circuit for energizing relay 100 may be traced from the energized conductor 93 through

conductor 153, winding 140 of relay 100, conductor 176, contact members 177 of relay 98 and conductors 175 and 157 to the energized conductor 92.

- The energization of relay 100 partly completes 5 a circuit for energizing the chain motor relay 102 to operate the chains in a reverse direction but which circuit is not entirely completed until the de-energization of the chain-forward time-limit relay 99. As soon as the chain-forward time-limit 10 relay 99 de-energizes after the time for which it has been set, the relay 102 is energized, the chain-motors 45 and 46 are plugged and the chains are caused to move in a reverse direction.

- The timing of relay 99 is so adjusted that the 15 sheet on which the rolling operation is being performed has been moved completely on to the catcher table 18 before the chains 33 and 34 are reversed. The timing of relay 100 is adjusted so that, even if the trailing end of the sheet moves to 20 disengage the catcher trigger switch 58, it will again be engaged before the relay 100 is de-energized.

- The circuit for energizing motor relay 102 may 25 be traced from the energized conductor 92 through conductor 157, contact members 178, of relay 100 which are now closed, conductor 179, winding 180 of relay 102, conductor 181, contact members 182 of relay 99, which are now closed, conductor 160 and conductor 153 to energized conductor 93.

- The energization of motor relay 102 completes 30 a circuit for locking itself in which may be traced from the energized conductor 93, through conductor 183, and contact members 184 of motor relay 102 to conductor 181 and over a circuit which has previously been traced to energized conductor 92.

- The operation of the elevator mechanisms will 35 now be set forth. It is desirable that the catcher table be elevated a predetermined time after the trailing end of the sheet leaves the passer table 17 but which time may be different from that desired for causing the reversal of the chains 33 and 34. As set forth hereinbefore, the passer trigger switch 57 is moved to the open position as soon as the trailing end of the sheet leaves the passer table 17. The trigger relay 97 is immediately de-energized and a predetermined time thereafter the relay 101 is de-energized, the time depending 40 upon the adjustment of the relay. The de-energization of the time-delay catcher elevator-up release the brake 84 and to energize the catcher elevator brake relay 110, which in turn serves to release the brake 84 and to energize the catcher elevator motor relay 112 to connect the catcher elevator motor 64 to the power source over an obvious circuit.

- The circuit for energizing the catcher elevator 45 brake relay 110 may be traced from the energized conductor 92 through conductor 157, contact members 185 of relay 107, which are closed a predetermined time after the sheet leaves the passer table 17, conductor 189, contact finger 122, contact segment 130 and contact finger 123 of the limit switch 82, conductor 187, winding 188 of the catcher elevator brake relay 110 and conductor 189 to the energized conductor 93.

- The circuit for energizing the catcher elevator 50 brake may be traced from the energized conductor 92 through conductor 151, contact members 190 of relay 110, conductor 191, solenoid 88 of the brake 84 and conductor 192 to energized conductor 93.

- The circuit for energizing motor relay 112 may 55 be traced from the energized conductor 93

through conductors 192 and 193, winding 194 of relay 112, conductor 195, contact members 196 of brake relay 110 to conductor 181 and thence through a circuit which has previously been traced to the energized conductor 92.

The energization of the catcher elevator motor 60 5 64 causes the catcher table 18 to be elevated to a position to clear the rolls 12 and 13, as indicated by the dotted position. At the same time, the limit switch 82 is rotated in the direction indicated by the arrow, and contact segment 132 is moved after the catcher table 18 has been moved to a predetermined position to complete a circuit for energizing the passer elevator brake relay 109. The energization of brake relay 109 causes the energization of the passer elevator motor relay 111 and in turn the energization of the passer elevator motor 63.

The circuit for energizing the passer elevator 65 10 brake relay 109 may be traced from the energized conductor 92 through conductors 157 and 191, contact finger 127, contact segment 132, contact finger 126, conductor 198, contact finger 113, contact segment 119, contact finger 114, conductor 199, winding 200 of relay 109, and conductor 192 to energized conductor 93.

The circuit for energizing the solenoid 87 of the passer elevator brake 83 may be traced from the energized conductor 92 through winding 87 of the brake 83, conductor 201, contact members 30 202, of the passer elevator brake relay 109, and conductor 192 to the energized conductor 93.

The circuit for energizing the passer elevator 35 15 motor relay 111 may be traced from the energized conductor 93 through conductors 192 and 203, winding 204 of motor relay 111, conductor 205, contact members 206 of brake relay 109, and through conductor 199 and over a circuit previously traced to the energized conductor 92.

Both elevator motors 63 and 64 are now energized and the tables 17 and 18 are elevated to the dotted positions shown in the drawings. After the upper limit of travel is reached, the contact segments 119 and 130 of the limit switches 81 and 82 respectively, open the circuits to brake relays 109 and 110, respectively, thereby de-energizing the motors 63 and 64 and applying the brakes 83 and 84. The contact fingers of limit switches 81 and 82 may now be considered to be in the position shown by the dotted lines A and B, respectively.

During the time when the tables 17 and 18 are being elevated the chain motors 45 and 46 are operating the chains 33 and 34 in the direction to return the sheet from the catcher table 18 over the top of the roll 12 to the passer table 17. The operation of the chains 33 and 34 is so arranged that a minimum amount of time is utilized in returning the sheet to the passer table 17, and by the time the catcher table 18 is in the full up position, the sheet is partly over the roll 12.

The former trailing end of the sheet has now become the leading end and when it engages the passer trigger switch 57 and returns to the passer table 17, the passer trigger relay 97 is again energized, whereupon the chain-forward time-delay relay 99 and the time-limit catcher elevator-up relay 107 are energized over circuits which have previously been traced.

The trailing end of the sheet on leaving the catcher table 18 releases the catcher trigger switch 58 and thereby de-energizes the catcher trigger relay 98. The de-energization of relay 98 initiates the de-energization of relays 108 and 75

100, which occurs after the time for which they have been set.

After a predetermined time, the chain-reverse time-limit relay 100 is de-energized, thereupon de-energizing chain-reverse motor relay 102 and completing a circuit for energizing chain-forward motor relay 101 which has previously been traced. The chains 33 and 34 thereupon reverse and again feed the sheet toward the rolls 11 and 12.

After the time has elapsed for which relay 108 has been set a circuit, which has previously been traced, will be completed for again energizing the catcher elevator brake relay 110. Energization of brake relay 110 releases the brake 84 and causes the energization of catcher elevator motor relay 112 to energize the catcher elevator motor 64 and initiate the movement of the catcher table 18 to the downward position.

20 The circuit for again energizing relay 110 may be traced from the energized conductor 92 through conductor 157, contact members 207 of relay 108 which are now closed, conductor 208, contact finger 125, contact segment 131, contact finger 124, conductor 187, winding 188 of relay 110, and conductor 189 to the energized conductor 93.

25 The circuits for energizing the brake 84 and the motor relay 112 have previously been traced and will not be repeated.

30 The downward movement of the catcher table 18 causes the movement of the limit switch 82 in the direction of the arrow, as previously set forth, so that at a predetermined position, the contact segment 133 bridges the contact fingers 128 and 129. A circuit is then completed for energizing the passer elevator brake relay 109 and thereby causing the release of the passer elevator brake 83 and the energization of passer elevator 35 motor relay 111 to energize passer elevator motor 63. The passer table 17 is then caused to move 40 in a downward direction.

35 The circuit for again energizing the passer elevator brake relay 109 may be traced from the energized conductor 92 through conductors 157 and 197, contact finger 128, contact segment 133, contact finger 129, conductor 209, contact finger 116, contact segment 120, contact finger 115, conductor 199, winding 200 of relay 109 and conductor 192 to energized conductor 93.

40 The circuits for energizing the passer elevator brake 83 and the passer elevator motor relay 111 have been previously traced, and will not be repeated.

45 The passer and catcher tables 17 and 18 continue to move in a downward direction until further movement thereof is arrested on operation of their respective limit switches 81 and 82, whereupon the brakes 83 and 84 serve to stop the 50 tables in the full downward position. Meanwhile, the chains 33 and 34 have been moved in a forward direction and the sheet is again passed between the rolls 11 and 12 and the foregoing operations are again repeated.

55 The timing of the relays 98, 100, 107 and 108, is so adjusted as to utilize a minimum time for carrying out a complete cycle of movement of the sheet from the passer table to the catcher table and back to the passer table. The timing may 60 be so adjusted that the sheet barely clears the roll 12 as the tables are moved upwardly or downwardly so that after the central position of the roll is reached, the end of the sheet adjacent the roll follows, in general, the contour of the 65 roll.

In the event that the operator wishes to gauge the thickness of the sheet, it is desirable that the sheet be returned to the initial position for convenience. In order to utilize a minimum time for the gauging operation it is desirable to operate the master control switch 91 to the "off" position while still continuing the automatic cycle of operation until the sheet is returned to the passer table 17 where it may readily be gauged. The operator may then leave his normal position 10 after moving the master switch to the "off" position and approach the passer table 17 to which the sheet will be returned and which will be lowered to the initial position.

In order to insure that a complete cycle of 15 operation will be performed after the passer elevator has moved upwardly, a predetermined distance, the contact segment 121 is provided on the limit switch 81. It will be observed that this contact segment completes a shunt circuit around 20 the master switch 91 and renders it ineffective to de-energize the control apparatus until the passer table 17 is again in the downward position.

The circuit which by-passes the master control 25 switch 91 may be traced from the energized conductor 93 through conductors 153 and 210, contact finger 118, contact segment 121, contact finger 117, conductors 211, 146 and 145, to the contact members 144 of the master switch 91.

It has been found that on the de-energization 30 of control apparatus due to the movement of the master switch 91 to the "off" position in order to stop the automatic functioning of the mill, there is a tendency for the chains 33 and 34 to coast 35 in the direction that carries the sheet away from the rolls 11 and 12. In order to prevent this coasting it is desirable to plug the chain motors 45 and 46 for a short interval of time and in some instances, to cause the actual reversal of the chains 33 and 34 to bring the sheet to a position 40 where it may be readily inspected.

In order to accomplish the plugging operation, the plugging relay 136 is provided, as hereinbefore set forth, and is energized on the energization of the chain-reverse time-limit relay 100. 45

The circuit for energizing relay 136 may be traced from the energized conductor 93 through conductor 153, winding 140 of relay 136, conductor 179, contact members 178 of relay 100 and conductor 157 to energized conductor 92. 50

The energization of the plugging relay 136 shunts the contact members 161 of relay 99 but causes no further operation until the de-energization of relay 100. On the de-energization of relay 100 and in the event that relay 99 is not 55 energized, the relay 136 serves to plug or reverse the operation of the chain motors 45 and 46, depending on the time for which the relay 136 is set. It will be observed that during the normal operating cycle the relay 136 serves merely 60 to shunt the contact members 161 which are already closed, and therefore, it does not effect the functioning of the system, except under the conditions previously set forth.

The circuit for shunting the contact members 65 161 may be traced from conductor 153 through contact members 212 of the plugging relay 136 and conductor 213 to conductor 162.

In the event that it is desired to operate the chain motors 45 and 46 in either a forward or 70 a reverse direction, independent of the automatic control system, push-button switches 214 and 215 are provided.

The circuit for energizing motor relay 101 to operate the chains in a forward direction man- 75

ually may be traced from energized conductor 93 through conductor 192, contact members 216 of switch 214, conductor 163, winding 164 of relay 101, conductor 165, contact members 166 of relay 100 and conductor 157 to energized conductor 92.

The circuit for energizing motor relay 102 manually to operate the chains in a reverse direction may be traced from the energized conductor 92 through conductor 151, contact members 217 of switch 215, conductor 179, winding 180 of relay 102, conductor 181, contact members 182 of relay 99 and conductor 153 to energized conductor 93.

15 In like manner the brake relays 109 and 110 may be manually controlled independently of the automatic control features to operate the elevator motors 63 and 64 as desired by means of push-button switches 219 and 220.

20 The push-button switch 219 controls the operation of the passer elevator brake relay 109 over a circuit which may be traced from energized conductor 92, contact members 221 of switch 219, winding 200 of relay 109 and conductor 192 to energized conductor 93.

The switch 220 controls the operation of the catcher elevator brake relay 110 over a circuit which may be traced from energized conductor 92 through conductor 151, conductor 222, contact members 223 of switch 220, winding 188 of relay 110, and conductor 189 to the energized conductor 93.

35 Since certain further changes may be made in the above construction and different embodiments of the invention may be made without departing from the scope thereof, it is intended that all matter contained in the above description or shown in the accompanying drawings shall be interpreted as illustrative and not in a limiting sense.

40 We claim as our invention:

1. In a control system for sheet rolling mills provided with a plurality of rolls, in combination, a passer table and a catcher table disposed on 45 opposite sides of the rolls, motor-operated feeding means on the passer table for passing the sheet between the rolls, motor-operated receiving means on the catcher table for conveying the sheet away from the rolls after a rolling operation has been performed, motor-operated elevating means individual to each table for operating the tables to a raised position to clear the rolls, a trigger switch on each table disposed to be actuated by the sheet passing thereover, control means responsive to the trigger switches for effecting the reverse operation of the motor-operated feeding and receiving means and initiating the movement of the motor-operated elevating means individual to the catcher table to the clear position a predetermined time after the sheet leaves the passer table and after it arrives on the catcher table, and control means actuated by the motor-operated elevating means of the catcher table for initiating the functioning of the motor-operated elevating means individual to the passer table after the catcher table is moved a predetermined distance from either its initial or raised position, the first-named control means also being disposed to effect the forward operation of the feeding and receiving means and initiating the movement of the elevating means individual to the catcher table to the initial position a predetermined time after the sheet leaves the catcher table and after it arrives on the passer table.

2. In a control system for sheet rolling mills provided with a plurality of rolls, in combination, a passer table and a catcher table disposed on opposite sides of the rolls, feeding means on the passer table for passing the sheet between the rolls, receiving means on the catcher table for conveying the sheet away from the rolls after a rolling operation has been performed, elevating means individual to each table for operating the tables to a position to clear the rolls, control means for effecting the reverse operation of the feeding and receiving means a predetermined time after the sheet leaves the passer table, additional control means for initiating the operation of the elevating means a predetermined time after the sheet leaves the passer table, and switch means operable in accordance with the movement of the elevating means for arresting further movement thereof after a predetermined movement, the first-mentioned control means being disposed to effect the forward operation of the feeding and receiving means a predetermined time after the sheet leaves the catcher table and the second-named control means being disposed to initiate the movement of the tables to the initial position a predetermined time after the sheet leaves the catcher table.

3. A control system for sheet rolling mills provided with a plurality of rolls and passer and catcher conveyor tables on opposite sides of the rolls for handling the material comprising, motor-operated elevating means individual to each table, a motor for driving the conveyor on each table, control means including a trigger switch on each of the tables for the motor-operated elevating means and the conveyor motors operable when initiated into operation to effect a predetermined cycle of operation thereof which comprises operating the table conveyors in the same direction with the tables in one position to pass the material through the rolls, reversing the direction of operation of the conveyors and initiating the operation of the catcher table elevating means at the expiration of a predetermined time after the material leaves the passer table and arrives upon the catcher table, initiating the operation of the passer table elevating means after the catcher table has moved a predetermined distance, stopping both the catcher and passer tables in a different predetermined position to cause the material to be passed back to the passer table, again reversing the direction of operation of the conveyors and again initiating the operation of the catcher table elevating means at the expiration of a predetermined time after the material leaves the catcher table and arrives upon the passer table, initiating the operation of the passer table elevating means after the catcher table has moved a predetermined distance toward its original position and stopping both the passer and catcher tables in their original positions, and a manually-operable switch for initiating the operation of the control means.

4. In an automatic control system for a sheet rolling mill provided with a plurality of rolls in which a complete automatic cycle of operation comprises passing the sheet through the rolls and returning it to be passed through again, in combination, passer means and catcher means for feeding the sheet to and receiving it from the rolls, elevating means for positioning the passer and catcher means, control means operable to effect the sequential operation of the passer and catcher means and the elevating means to produce a complete automatic cycle of operation,

manually operable means for initiating the operation of the control means, and additional control means for rendering the manual means ineffective to arrest the cycle of operation until the sheet is returned to the initial position.

5. In a system for automatically controlling the operation of the feeding mechanism for a sheet rolling mill provided with a plurality of rolls, in combination, a passer table and a catcher table disposed on opposite sides of the rolls, feeding means on the passer table for passing the sheet between the rolls, receiving means on the catcher table for conveying the sheet away from the rolls after a rolling operation has been performed, elevating means individual to each table for operating the tables to a position to clear the rolls, adjustable timing means for initiating the functioning of the elevating means and of the feeding and receiving means in a reverse direction 10 a predetermined time after the sheet leaves either of the tables and after it arrives on the other table, control means operable in accordance with the movement of the elevating means for arresting further movement of the elevating means 15 after a predetermined movement thereof, manually-operable means for initiating the functioning of the timing means, and means for rendering the manual means ineffective to arrest the functioning of the feeding mechanism until after 20 a predetermined cycle of operation has been performed.

6. In an automatic control system for sheet rolling mills provided with a plurality of rolls, in combination, a passer table and a catcher table disposed on opposite sides of the rolls, feeding means on the passer table for passing the sheet between the rolls, receiving means on the catcher table for conveying the sheet away from the rolls after a rolling operation has been performed, 25 elevating means individual to each table for operating the tables to a position to clear the rolls, timing means for initiating the functioning of the elevating means and of the feeding and receiving means in a reverse direction a predetermined time after the sheet leaves either of the tables and after it arrives on the other table, control means operative in accordance with the movement of the elevating means for arresting further movement of the elevating means after a 30 predetermined movement thereof, manually-operable means for initiating the functioning of the timing means, and automatic means for independently causing the operation of the feeding means to feed the sheet toward the rolls prior to completion of a cycle of operation and after the manually operable means has been operated to the initial position.

7. In an automatic control system for sheet rolling mills provided with a plurality of rolls, in combination, a passer table and a catcher table disposed on opposite sides of the rolls, feeding means on the passer table for passing the sheet between the rolls, receiving means on the catcher table for conveying the sheet away from the rolls after a rolling operation has been performed, elevating means individual to each table for operating the tables to a position to clear the rolls, timing means for initiating the functioning of the elevating means and of the feeding and receiving means in a reverse direction a predetermined time after the sheet leaves either of the tables, control means for arresting further movement of the elevating means after a predetermined movement thereof, manually-operable 55 means for initiating the functioning of the tim-

ing means, means for rendering the manual means ineffective to arrest the functioning of the feeding mechanism until after a predetermined cycle of operation has been performed, and automatic means for independently causing the operation of the feeding means to feed the sheet toward the rolls prior to the completion of a cycle of operation and after the manually-operable means has been operated to the initiated position.

8. In an automatic control system for sheet rolling mills provided with a plurality of rolls, in combination, a passer table and a catcher table disposed on opposite sides of the rolls, feeding means on the passer table for passing the sheet between the rolls, receiving means on the catcher table for conveying the sheet away from the rolls after a rolling operation has been performed, elevating means individual to each table for operating the tables to a position to clear the rolls, 15 timing means for initiating the functioning of the elevating means and of the feeding and receiving means in a reverse direction a predetermined time after the sheet leaves either of the tables and after it arrives on the other table, control means operative in accordance with the movement of the elevating means for arresting further movement of the elevating means after a predetermined movement thereof, manually-operable 20 means for initiating the functioning of the timing means, means for rendering the manual means ineffective to arrest the functioning of the feeding mechanism until after a predetermined cycle of operation has been performed, and automatic 25 means for independently causing the operation of the feeding means to feed the sheet toward the rolls prior to the completion of a cycle of operation and after the manually-operable means has been operated to the initial position.

9. In a control system for sheet rolling mills provided with a plurality of rolls and passer and catcher conveyor tables on opposite sides of the rolls movable between lower and upper positions, a motor for driving the conveyor on each table, motor-operated elevating means for each table, 40 a trigger switch on each table disposed to be actuated by the material passing thereover, timing means controlled by said trigger switches for reversing the direction of operation of the conveyor motors and initiating the operation of the elevating means on the catcher table at the expiration of a predetermined time interval after the material leaves either of the tables and arrives upon the opposite table, means actuated in accordance with a predetermined movement of 45 the catcher table in either direction for initiating the operation of the elevating means on the passer table and for further controlling the motor-operated means on the catcher table to stop said table after a predetermined movement thereof in either 50 direction, and switch means actuated in accordance with the movement of the passer table in either direction for further controlling its motor-operated elevating means to stop said table after a predetermined movement in either direction. 55

10. In a control system for sheet rolling mills provided with a plurality of rolls, in combination, a passer table and a catcher table disposed on opposite sides of the rolls, feeding means on the passer table for passing the sheet between the 70 rolls, receiving means on the catcher table for conveying the sheet away from the rolls after a rolling operation has been performed, elevating means individual to each table for operating the tables to a position to clear the rolls, adjustable 75

timing means for initiating the functioning of the elevating means individual to the catcher table and of the feeding and receiving means in a reverse direction a predetermined time after the sheet leaves either of the tables and after it arrives on the other table, and control means operable in accordance with the movement of the elevating means individual to the catcher table for initiating the functioning of the elevating means individual to the passer table and for arresting further movement of the elevating means individual to the catcher table after the catcher table is moved to a predetermined position.

11. In a control system for sheet rolling mills provided with a plurality of rolls, in combination, a passer table and a catcher table disposed on opposite sides of the rolls, feeding means on the passer table for passing the sheet between the rolls, receiving means on the catcher table for conveying the sheet away from the rolls after a rolling operation has been performed, independently-operable elevating means individual to each table for operating the tables to a position to clear the rolls, time delay control means for effecting the reverse operation of the feeding and receiving means and initiating the functioning of the elevating means of the catcher table a predetermined time after the sheet leaves the passer table and after it arrives on the catcher table, and control means actuated by the catcher table elevating means for initiating the operation of the passer table elevating means and for arresting further movement of the catcher table elevating means after the catcher table has moved a predetermined distance, control means actuated by the passer table elevating means for arresting further movement thereof after the passer table has moved a

predetermined distance, the first-mentioned control means being adapted to again effect the forward operation of the feeding and receiving means and to initiate the movement of the catcher table elevating means to the initial position a predetermined time after the sheet leaves the catcher table and after it arrives on the passer table, and the second-mentioned control means being adapted to again initiate the operation of the passer table elevating means to return it to the initial position.

12. In a system for automatically controlling the operation of the feeding mechanism for a sheet rolling mill provided with a plurality of rolls, in combination, a passer table and a catcher table disposed on opposite sides of the rolls, feeding means on the passer table for passing the sheet between the rolls, receiving means on the catcher table for conveying the sheet away from the rolls after a rolling operation has been performed, elevating means individual to each table for operating the tables to a position to clear the rolls, adjustable timing means for initiating the functioning of the elevating means and of the feeding and receiving means in a reverse direction a predetermined time after the sheet leaves either of the tables, control means for arresting further movement of the elevating means after a predetermined movement thereof, manually operable means for initiating the functioning of the timing means, and means for rendering the manual means ineffective to arrest the functioning of the feeding mechanism until after a predetermined cycle of operation has been performed.
